UNITED STATES PATENT OFFICE.

LIZZIE BARKER CRITZ, OF WEST POINT, MISSISSIPPI.

DESIGN FOR A DISH.

No. 38,094.

Specification for Design.

Patented June 19, 1906.

Application filed May 5, 1906. Serial No. 315,452. Term of patent 7 years.

To all whom it may concern:

Be it known that I, LIZZIE BARKER CRITZ, a citizen of the United States, residing at West Point, in the county of Clay and State of Mississippi, have invented a new, ornamental, and original Design for a Dish, of which the following is a specification, reference being had to the accompanying drawings, in which—

view of the same. Fig. 3 is a vertical longitudinal sectional view of the dish.

The design is shown in the drawings described above.

What I claim is—

The ornamental design for a dish, as shown in the drawings.
